REGISTERING APPARATUS

Alfred J. Hammel, Stockton, Calif., assignor to
 Fibreboard Products Inc., San Francisco, Calif.,
 a corporation of Delaware

Application April 9, 1951, Serial No. 220,041

21 Claims. (Cl. 216—9)

1

This invention relates to an apparatus and method for the registering of objects in predetermined relationship, and more particularly to registering a strip of material in the form of a carton blank with another strip of material in the form of a tab adapted to be secured to the blank, although the principle of the invention is applicable to registering other forms of objects.

A type of carton for which the invention has found great applicability is disclosed in Patent No. 2,288,914, dated July 7, 1942, in which the carton blank is provided with a slotted portion to form a hinged flap that can be opened. Underneath such flat portion is adhesively secured a closure strip or tab which is adapted to cover the opening which is formed by the flap when it is opened. This closure tab is also provided with a slotted spout forming portion adhesively secured to the flap of the blank so that when the flap is opened, a pouring spout is formed. The blank is provided with a transverse crease adjacent the top; and the closure tab is also provided with a transverse crease adapted to register with the crease of the blank. Unless these creases are registered substantially accurately, leakage of the contents of the carton may occur. The necessity for accurate registry of the creases thus becomes apparent.

Summarizing this invention, it comprises continuously feeding to registering mechanism successive objects of one set of objects which in the embodiment of the invention illustrated are the carton tabs; and also continuously conducting to the registering mechanism successive objects of another set of objects which in the embodiment of the invention illustrated are the carton blanks. The blanks and the tabs are conducted with an uninterrupted motion and in the same direction to the registering mechanism which has driven means including a plurality of series of abutment elements. One series of elements is provided for engaging the successive tabs; and another series of elements is provided to engage the successive blanks.

The tab abutment elements are so arranged with reference to the tabs as to engage and positively move the successive tabs to the registering mechanism, while the blank abutment elements are so arranged with reference to the blanks as to engage with and be driven by the successive blanks under the force which conveys the blanks to the registering mechanism. The driven means including the abutment elements are driven by driving means which has a loose coupling or driving connection with the

driven means; and the blanks are fed in the path of the blank abutment elements of the driven means at a linear velocity greater than the linear velocity at which such abutment elements are driven. As a result, each time the respective blanks engage the respective abutment elements therefor, the drive between the driven means and the driving means is temporarily and automatically disconnected. Each time this occurs, instead of the driving means driving all the abutment elements in unison, the respective blanks serve to effect the driving of such elements in unison and in advance of the driving means.

The respective tab abutment elements and the respective blank abutment elements of the respective series thereof, are so spaced apart as to position the respective blanks and tabs in desired relationship for proper registry between the aforementioned creases. Such registry is maintained during the entire period that the successive blanks drive the cooperating abutment elements therefor because the registering mechanism is free from the driving influence of the driving means which drives the registering mechanism during the period when the respective blanks do not drive their respective cooperating abutment elements. As a result, substantially at the end of the blank driving period the respective blanks and tabs can be adhesively secured together with the creases thereof in substantially exact registry.

Referring to the drawings, which illustrate a preferred embodiment of the invention adapted for the registering of objects of the type described:

Fig. 1 is a plan view of a common form of carton blank adapted to be folded into the shape illustrated in the aforementioned patent, and which is commonly employed for the packaging of milk.

Fig. 2 is a plan view of the closure tab or strip adapted to be secured to the inside face of such blank;

Fig. 3 is a fragmentary plan view illustrating the positioning of the tab of Fig. 2 on the blank of Fig. 1;

Fig. 4 is a fragmentary section taken in a plane indicated by the line 4—4 of Fig. 3;

Fig. 5 is a fragmentary schematic side elevational view of a common form of machine for forming the tabs and adhesively securing them to preformed blanks. In such view, the registering mechanism of this invention is also shown schematically;

Fig. 6 is a fragmentary plan view of the por-

tion of the machine embodying the registering mechanism, shown in Fig. 5; portions of the structure being omitted from the view to disclose more clearly the construction;

Fig. 7 is an enlarged plan view of the registering mechanism;

Fig. 8 is a side elevational view of the registering mechanism, looking in the direction of arrow 8 in Fig. 6; portions of the structure being omitted from the view to disclose more clearly the construction;

Fig. 9 is a vertical sectional elevation illustrating the tab conveying chain of the registering mechanism; the section being taken in planes indicated by line 9—9 in Fig. 7 and portions of the structure being omitted from the view to disclose more clearly the construction;

Fig. 10 is a vertical sectional elevation of the blank chain of the registering mechanism, taken in a plane indicated by line 10—10 in Fig. 7; portions of the structure being omitted from the view for purposes of clarity and only one blank being shown in Fig. 10 for purposes of clarity;

Fig. 11 is a transverse vertical section taken in a plane indicated by line 11—11 in Fig. 7; a registered blank and tab being shown in this view in the nip of the pressure rollers;

Fig. 12 is a vertical sectional elevation taken in a plane indicated by line 12—12 in Fig. 7; portions of the structure being omitted from the view for purposes of clarity;

Fig. 13 is a fragmentary horizontal sectional elevation, illustrating a shoe engaging the under-reach of the blank chain; the plane of the section being indicated by line 13—13 in Fig. 8;

Fig. 14 is a vertical sectional elevation taken in planes indicated by line 14—14 in Fig. 12; portions of the structure being omitted from the view to illustrate more clearly the construction;

Fig. 15 is an isometric view of a portion of the upper-reach of the tab chain, illustrating one of the hook members thereon for engaging a tab; the direction of the view being indicated by arrow 15 in Fig. 9;

Fig. 16 is a view similar to Fig. 15 of a portion of the upper-reach of the blank chain, illustrating the blank engaging hook member thereon; the direction of the view being indicated by direction arrow 16 in Fig. 10;

Fig. 17 is a fragmentary elevational view looking in the direction of arrow 17 in Fig. 10;

Fig. 18 is a schematic side sectional elevational view of portions of the under-reaches of the tab and blank chains, illustrating the relative position of the hook members on such chains and the engagement of a tab and a blank with such hook members, as these objects move toward the pressure rollers of the apparatus.

As illustrated in Fig. 1, the carton blank 1 is of paperboard provided with crease or score lines 2 that have their raised portions facing inwardly of the blank and which are illustrated by dotted lines in the figure. Cuts 3, shown in solid lines, are also provided to form bottom closing flaps of the carton. The blank is adapted to be set up in the manner illustrated in the aforementioned patent. Side panel 6 and inwardly foldable top panel 7 have formed therein flap portion 8 which extends across crease line 2' between such panels. Flap 8 may be opened by virtue of the fact that it is bound by side incision lines 9. An opening 11 is formed below the lower end of flap 8 to enable grasping of the lower end of the flap, so that it may be pulled open by tearing along incision lines 9.

Closure tab 12, also of paperboard, is provided with an inside crease line 13, and is adapted to be adhesively secured over flap 8, crease line 2' and opening 11 with crease line 13 registering with carton blank crease line 2', as is illustrated in Figs. 3 and 4. Flap 14 is formed in tab 12 to provide a pouring spout opening when blank flap 8 is opened. For this purpose, flap 14 is adhesively spot-glued to the inside face of flap 8. Side and bottom incision lines 16 are provided in tab 12 to enable opening of flap 14 with flap 8; the top of flap 14 having a hinged connection 17 in tab 12. The zone of adhesive union between tab 12 and the carton blank is illustrated by the stippling in Fig. 3. With reference to Fig. 4, it will be noted that unless creases 2' and 13 are substantially accurately registered or aligned, leakage may occur between closure tab 12 and the carton blank; particularly since the set up blank is ultimately folded along such creases before the carton is filled with a liquid, such as milk for which the carton is particularly adapted as a container therefor.

In the conventional machine for forming the tabs and securing them to the blanks, illustrated schematically in Fig. 5 which also shows the registering mechanism of this invention, one common form of which is known in the trade as the International Machine, manufactured by "The International Paper Box Machine Company," carton blanks 1 are positively conveyed or fed in one general direction by being held between the upper reach of a relatively wide continuously moving endless belt 21 and the under-reaches of a pair of laterally spaced relatively narrow belts 22 which are driven in unison and at the same velocity as belt 21 from the main drive of the machine. The blanks which are held between belts 21 and 22 are previously formed, creased and cut, and are supplied between the belts by a conventional form of feed stacker mechanism (not shown).

The upper reach of belt 21 runs over the usual spring thrust tensioning rollers 23; and a plurality of spaced transversely extending rods 24, secured to the frame of the machine, are positioned over and adjacent the under-reach of belts 22 to stabilize movement of the cooperating blank conveying reaches of the belts in a substantially constant plane. Belts 22 are provided with the usual belt tensioning mechanism 25.

Tabs 12 are formed from a continuous strip 26 of paperboard which runs under a guide roll 27, and is supplied from a supply roll of such material (not shown). From guide roll 27, strip 26 passes between rollers 28 which are provided with conventional means to form creases 13 at predetermined spaced intervals along the strip, and to provide incision lines 16 and hinge line 17 at such intervals for formation of openable flap 14.

Feed rollers 29, driven in the usual manner from the machine by any suitable connecting drive means (not shown), are provided to feed continuously the strip which although incised and creased at rollers 28 is not severed into individual tabs at such location. Next, adhesive is applied at the desired spaced locations on the strip, by means of the customary adhesive applying mechanism including rollers 31 which are driven from the drive of the machine in any suitable manner (not shown), and which are provided with the usual means for applying the adhesive in the desired pattern. The strip next passes through cutting rollers 32 which are also

driven in any suitable manner (not shown) from the machine, and which are provided with the usual cooperating means to cut the strip transversely so that individual tabs are formed.

From the preceding, it is seen that the set of successive blanks is fed in one general direction by being held between continuously moving belts 21 and 22, while strip 26 from which tabs 12 are formed is fed in the same general direction as the blanks, by feed rollers 29. The plane of feeding of strip 26 is, however, inclined relative to the plane of feeding of the individual blanks, so that tabs 12, which are formed from strip 26, will meet the respective blanks at a predetermined location above the blanks. The described mechanism is more or less conventional.

Registering mechanism, indicated generally by reference character R, is provided adjacent the location at which the respective tabs meet the respective blanks, to effect substantially exact registry or alignment between respective creases 13 of the respective tabs and the respective creases 2' of the respective blanks. Such registering mechanism is associated with pressure rollers to be described hereinafter for effecting adhesive unison between the respective tabs and respective blanks after they have been properly registered.

With registering mechanism heretofore employed in machines of the type described, suitable separating mechanism, indicated generally by reference character S, and including a pair of cooperating rollers 33 and 34, is provided to effect complete separation of the respective tabs 12 from strip 26; and such tab separating mechanism S is also associated with the registering mechanism of this invention. Rollers 33 and 34 are driven at a slightly greater speed than the speed at which strip 26 is driven, and as a result, the tabs become completely separated.

In such prior registering mechanism, a single registering chain, having suitable spaced abutment elements to engage the respective tabs 12 was provided to move the tabs positively down a conventional guide-way to be described hereinafter. The spacing between the abutment elements on said chain was such as to obtain theoretically proper registry of the aforementioned creases on the tabs with those on the blanks. However, such registry could not be properly obtained because it is extremely difficult to time or synchronize movement of a chain exactly with movement of a belt.

With respect to the registering mechanism R of this invention, such registry can be maintained with great accuracy, so that when the respective tabs and respective blanks leave the registering mechanism and are engaged by the pressure means which applies the pressure to unite adhesively the respective blanks with the respective tabs, the aforementioned creases will be accurately aligned. This is accomplished by freeing the registering mechanism completely from the drive of the machine during the registering periods, by causing the objects of one of the sets of successive objects to drive the registering mechanism while registry is maintained with the respective objects of the other set.

The registering mechanism R hereof is driven by means including drive chain 36, one turn of which is connected to the registering mechanism and the other turn of which passes around a sprocket 37 mounted on a shaft 38 which is connected to sprocket 39 in turn connected to a

chain 41 connected to the main drive (not shown) of the machine. Shaft 38 also carries pulleys 41' of the desired diameter to drive narrow belts 22 at the desired speed. Mechanism R and associated parts are supported from frame member 42 of the machine in the form of an I-beam which extends over wide belt 21 and is spaced therefrom.

Referring particularly to Figs. 7 and 11, the support for the registering mechanism includes support shaft 43 fixedly secured on frame member 42 by nut 44. Shaft 43 has a mounting portion 46 in frame member 42, which is eccentrically positioned with respect to the main body portion of the shaft so that turning of portion 46 in frame member 42 can effect adjustment of the height of the main body portion of shaft 43 above the blank conveying mechanism to provide for proper relative positioning between the registering mechanism and the blank conveying mechanism.

At its end adjacent frame member 42, shaft 43 has journalled thereon a sleeve 47 which has fixedly secured thereto a sprocket 48 forming part of the registering mechanism driving means and which is connected to the previously mentioned chain 36. Spaced pressure rollers 49 are also fixedly secured to sleeve 47 and are consequently rotatable therewith as part of the driving means. Positioned between pressure rollers 49 and journalled on suitable roller bearings 51 on sleeves 47 so as to be rotatable independently of the driving means is a sprocket hub 52 having sprocket 53 secured thereto and about which passes a chain 54 which has suitable spaced abutment elements to be described more fully hereinafter for engaging the respective tabs.

The right hand pressure roller 49 appearing in Fig. 11 is provided with an arcuate slot 56 (Fig. 9); and a coupling pin 57 fixedly connected to hub 52 of sprocket 53 extends through arcuate slot 56 and projects therebeyond to provide a positive connection between sprocket 53 and another sprocket 58 which is journalled for rotation about shaft 43. A chain 59 having spaced abutment elements to be described and adapted to be engaged by the respective blanks, passes about sprocket 58. Sprocket 58 is secured for angular adjustment on a hub member 61, by means of cap screws 62 each of which passes through an arcuate slot 63 in hub 61. Hub 61 is journalled for rotation about support shaft 43 by means of roller bearings 64; and the hub has a recess 66 in which is removably received the pin 57 which positively connects sprockets 53 and 58 for rotation in unison.

A spacer collar 67 is positioned between sleeve 47 and hub 61. The free or right hand end of shaft 43 appearing in Fig. 11 supports an outside frame plate 68 of the registering mechanism; such plate 68 being fixedly held in adjusted position on support shaft 43 by means including screw 69. A spacer 71 is positioned between frame plate 68 and sprocket 58, and is fixedly held in position on shaft 43 by means including screw 72.

From the preceding, it will be observed that sprockets 53 and 58 form part of the driven means of the registering mechanism and are always driven in unison and at the same speed whenever pin 57 is engaged by the right hand boundary portion of arcuate slot 56 appearing in Fig. 9. Also, pressure roller 49 containing such slot 56 forms part of the driving means. However, because of the loose coupling or driv-

ing connection provided by pin 57 and arcuate slot 56, the drive between the driving means and the driven means can be disconnected or disengaged. In this connection, it will be noted that the diameters of sprockets 53 and 58 are the same so that the respective chains 54 and 59 will always be driven in unison at the same linear velocity, and consequently provide an endless chain structure having an underlying reach and an overlying reach.

Means is provided for supporting the opposite turns of the respective chains 54 and 59. With particular reference to Fig. 9, the overlying reach of chain 54, which has the elements for engaging the respective tabs, passes over an idler sprocket 73 which is journaled on a bracket 74 fixedly secured to frame member 42. From the turn about sprocket 73, chain 54 has an upright reach inclined inwardly toward its underlying reach, which passes over another idler sprocket 76 (Fig. 12). Sprocket 76 is journaled for rotation about a rotatable shaft 77 journaled in frame member 42; shaft 77 being rotatable for a purpose to be subsequently explained. The underlying reach of chain 54 then passes over driven sprocket 53. A guide shoe 78 is provided over the upper side of the underlying reach of chain 54 to engage the chain and thereby maintain such reach of the chain in a predetermined plane; guide shoe 78 being supported on shafts 79 fixedly secured to frame member 42.

From sprocket 58, the upper reach of chain 59 passes over an idler sprocket 81 journaled on a pin 82 which is adjustably but fixedly mounted on frame plate 68 by means of mounting of pin 82 in a slot 83 provided in plate 68, and lock nut 84 for fixedly holding pin 82 in adjusted position in accordance with the tension to be imparted to the chain. As with respect to chain 54, chain 59 has an upright reach inclined inwardly toward its underlying reach and which passes over another idler sprocket 86 fixedly journaled on frame plate 68. The underlying reach of chain 59 passes substantially parallel to and closely adjacent over belt 21. A guide shoe 87 is adjustably supported on frame plate 68; and engages the upper side of the underlying reach of chain 59 to hold the same in proper relation with respect to belt 21. The adjustment for shoe 87 is obtained by means of slots 88 in frame plate 68 in which pins 89 are adjustably held by means of nuts 91. It will be noted that tab chain 54 projects in advance of blank chain 59 for a purpose to be explained.

Tab separating mechanism S cooperates with tab chain 54; and includes the previously mentioned rollers 34, one at each side of sprocket 76 and which are fixedly secured for rotation with the previously mentioned rotatable shaft 77. Shaft 77 extends through frame member 42; and on the projecting end thereof, it has secured thereto a sprocket 92 connected to a chain 93 which in turn is connected to a sprocket secured to the previously mentioned shaft 38, so that shaft 77 is continuously rotated from the drive of the machine.

Shaft 77 also has secured thereto for rotation therewith a pinion 94 which meshes with a gear 96 having a floating engagement with pinion 94. To provide for such floating engagement, gear 96 is fixed to a shaft 97 which is journaled in spaced arms 98 secured to a shaft 99 projecting through and pivoted in frame member 42. The projecting end of pivot shaft 99 is connected to an upright arm 101 which is resiliently urged

in such direction by a spring 102 connected to frame 42, to cause the floating meshing engagement of pinion 94 with gear 96. Also, fixedly secured for rotation with shaft 97 are the pair of spaced rollers 33 which cooperate with the respective rollers 34. Each of these rollers 33 is provided with an increased diameter cam portion 104.

Leading from the tab severing rollers 32 and 10 extending to a position adjacent pressure rollers 49 is a pair of laterally spaced guides 106 inclined downwardly toward pressure rollers 49. Each guide 106 has a groove 107 in its inner side; the tabs engaging and being slidable in such grooves 107. Guides 106 are supported by the previously mentioned shafts 79, by means of hangers 108 fixedly attached to the shafts and to the guides. Guides 106 are also supported in the usual manner on the frame work (not shown) of the severing rollers 32.

In the severing rollers, the tabs, although cut from the parent strip of material 26, are not individually separated in spaced relationship. However, when such cut strip passes between the cooperating pairs of separating rollers 33 and 34, the drive gearing for which is such as to cause them to rotate at a greater peripheral speed than the speed at which the parent strip is moved, complete severance and spaced separation of the respective tabs from the parent strip is effected. Cam portions 104 on rollers 33 provide a so-called kicker action to insure separation of the tabs in substantially uniform spaced relationship. After such separation, the tabs are 30 free of any driving connection with the strip but are then respectively positively engaged by abutment elements on tab chain 54 to be positively conducted down inclined guides 106 to pressure rollers 49.

40 The abutment elements on tab chain 54 comprise hook members 109 pivotally mounted thereon at predetermined uniformly spaced intervals. Each hook member 109 comprises a pair of spaced arms 111, one at each side of chain 54 and pivotally connected to the chain on pivot pin 112. At one end, arms 111 are connected to an abutment element 113 extending over the outer face of the chain. At the opposite end, each of arms 111 is provided with a stop 114 adapted to engage over a projecting stop pin 116 on the chain.

Cooperating stops 114—116 on each hook member 109 serve to hold the abutment element 113 thereon in position to engage positively an edge 55 of a tab as the abutment element sweeps around to the underlying reach of the chain, and as such tab is fed thereto by tab separating mechanism S. The inward inclination of the upright reach of chain 54, joining the overlying and 60 underlying reaches, toward the underlying reach at the turn where the respective abutment elements 113 engage the respective tabs, insures that the hook members 109 will fall in proper position as they approach the underlying reach 65 where the respective abutment elements 113 engage the respective tabs. In this connection the abutment elements 113 on tab chain 54 will always positively engage the rear edges of the respective tabs (with reference to the 70 direction of their travel along guides 106) and move them by pulling them along guides 106 toward pressure rollers 49 at which location the respective tabs meet the respective blanks.

Uniformly spaced hook members 117 are pivotally mounted on blank chain 59 to become en-

gaged with the respective blanks as they are continuously moved toward the pressure rollers 49 by the belt driving means 21 and 22. Hook members 117 are essentially the same as the hook members 109. Consequently, the reference numerals applied to the hook members 109 are applied to the corresponding parts of hook members 117, except that those for the latter are primed. Although, hook members 109 and 117 are essentially the same in construction, their relative position on the respective chains 54 and 59 is different.

It will be noted that hook members 117 are positioned in a direction opposite to the positioning of hook members 109, so that the respective abutment elements 113' of respective hook members 117 will be in such position as to cause the front edges of the respective blanks to engage elements 113' in a direction to drive chain 59, and consequently chain 54 since it is positively connected for movement in unison with chain 59, by pin 57. The upright turn of chain 59 connected between the overlying and underlying reaches of such chain, extends inwardly toward the underlying reach of the chain for the same purpose described with respect to the corresponding turn of chain 54.

To guide hook members 117 in proper position flat over belt 21 in their passage about the turn of sprocket 86, a laterally projecting pin 118 is fixedly secured to each side of each of spaced arms 111' of each hook member 117 and adjacent the abutment element 113' of such hook members. These pins ride against the curved arms 118' of a forked guide member 119 fixedly secured to frame plate 68 of the registering device by means of screw 121; the lower end of guide member 119 being slotted at 122 to provide arms 118' and to permit the abutment elements 113' to pass between the arms while the pins engage the arms. The respective abutment elements 113' are adapted to engage an inclined edge 123 of the respective carton blanks, and consequently the engaging face of each abutment element 113' is inclined to the same angle.

Operation.—The direction of movement of the various elements is indicated by the direction arrows. The right hand pressure roller 49 appearing in Fig. 11 forms part of the drive means for driving the driven means of the registering mechanism which includes the chains 54 and 59. Sprockets 53 and 58 for the respective chains, since they are coupled together by connecting pin 57, will always be rotated in unison and at the same peripheral velocity inasmuch as the sprockets 53 and 58 are of the same diameter. Consequently, chains 54 and 59 will always be driven at the same linear velocity. By virtue of the loose coupling or driving connection between pin 57 and driving roller 49, the drive between the driving means and the driven means can be disconnected or declutched; and both of chains 54 and 59 can be driven temporarily independently in advance of the driving means.

The respective tabs are always positively moved down guideways 106 because they are always positively fed in the path of the respective abutment elements 113 which positively engage the tabs. Right after they leave guideways 106, the respective tabs are clamped in the nip of pressure rollers 49 acting against endless belt 21, and are adhesively pressed and secured to the respective blanks as they meet such blanks underneath the pressure rollers 49, adhesive having been pre-

viously applied at the proper locations to the respective tabs.

Although the abutment elements 113 on hook members 109 positively move or drive the respective tabs through the registering mechanism, the abutment elements 113' on hook members 117 of blank chain 59 are so positioned as to cause the respective blanks to drive chain 59 throughout the passage of each blank through the registering mechanism and upon engagement of an edge of such blank with an abutment element 113' as the respective blanks are moved in the path of abutment elements 113' by belts 21 and 22.

Belts 21 and 22 are driven at a greater linear velocity, preferably at about 7% greater speed, than the linear velocity imparted to chains 54 and 59 when under the positive influence of the positive drive of the driving means which is effected when pin 57 contacts the right boundary of arcuate slot 56 appearing in Fig. 9. Hence, whenever the edge of a blank engages an abutment element 113' on a hook member 117, such blank will temporarily disconnect the drive and cause both of the registering chains 54 and 59 to be temporarily driven solely by the engaged blank which is positively moved at all times by belts 21 and 22.

As is indicated schematically in Fig. 18, the spacing between the faces of the respective abutment elements 113 and 113' which are adapted to engage the edges of the respective tabs and blanks, is such that when a tab engages an abutment element 113 and a blank engages an abutment element 113', the crease line 13 on the tab and the crease line 2' on the blank will be aligned in correct registry. In this connection, the correct spacing can be initially obtained by angular adjustment of sprocket 58 on its mounting hub 61.

The tab receiving turn of tab chain 54 is positioned ahead of the blank receiving turn of blank chain 59. Hence, each of the successive tabs will become engaged by an abutment element 113 prior to the time that an abutment element 113', becomes engaged with a blank to which the tab is adapted to be secured. Before such blank becomes engaged with such abutment element 113', the tab previously engaged by an abutment element 113 will be positively moved through the positive drive imparted to chain 54 by the machine. However, at the instant the blank to which such tab is adapted to be secured engages an abutment element 113', the drive will be automatically temporarily disconnected in the manner previously related; and that blank will serve to drive both chains 54 and 59 of the registering mechanism (and consequently the tab adapted to be secured thereto) throughout the remainder of the passage of the blank through the registering mechanism.

Thus, the registry effected between the driving blank and the tab adapted to be secured thereto, by virtue of the spacing between the respective abutment elements 113 and 113', can not be altered or otherwise affected because the registering mechanism is free of influence from the drive of the machine. Consequently, the registering of the creases in question initially provided for by the spacing between the respective abutment elements 113 and 113' will be maintained to the point where the respective blanks and respective tabs become engaged under the nip of the pressure rollers 49. In this connection, arcuate slot 56 is made sufficiently long, so that pin 57 cannot engage the left hand boundary portion of the slot 56 appearing in Fig. 9.

11

during the period that each successive blank serves as the driving means for the registering mechanism.

Pressure rollers 49 rotate about the axis of rotation of sprockets 53 and 58. Consequently, their position is such with reference to chains 54 and 59, that abutment elements 113 and 113' become disengaged from the respective tabs and blanks substantially when they enter the nip of the pressure rollers. As a result, the registry initially effected between a blank and a tab will be maintained until these parts are clamped in the nip of the pressure rollers.

After a tab has been adhesively united to a blank in its passage through the pressure rollers 49, and before blank chain 59 is again driven by another succeeding blank, there will be no positive drive imparted to chains 54 and 59 until pin 57 becomes again engaged with the right hand boundary of arcuate slot 56 appearing in Fig. 9 whereupon the registering mechanism is in position for effecting registry between the next blank of the series or set of blanks, and the next tab of the series or set of tabs. In this connection, it is to be understood that the blanks and tabs are fed rapidly and their passage through the registering mechanism is only for a minor fraction of a second.

Upon leaving the pressure rollers 49, the adhesively secured blanks and tabs, are then folded and otherwise handled in the usual manner accomplished by the usual mechanism (not shown) embodied in the type of machine described.

I claim:

1. Apparatus for effecting registry of objects comprising driven means having elements for engaging the respective objects and positioning them in desired relation for such registry, means for driving said driven means, and a loose driving connection between said driven means and said driving means for allowing disconnection of the drive therebetween upon engagement of an object with one of said elements.

2. Apparatus for effecting registry of objects comprising driven means having a series of elements for engaging successive objects of a set of such objects and another series of elements for engaging successive objects of another set of such objects, the respective elements of the respective series being spaced to position said objects in desired relation for such registry, means for driving said driven means, and a loose driving connection between said driven means and said driving means for allowing disconnection of the drive therebetween upon engagement of the respective objects of one of said sets of objects with the respective elements of one of said series of elements.

3. Apparatus for effecting registry of objects comprising driven means having a series of elements for engaging successive objects of a set of such objects and another series of elements for engaging successive objects of another set of such objects, the respective elements of the respective series being spaced to position said objects in desired relation for such registry, means for driving said driven means, means for conducting one of said sets of objects in the path of one of said series of elements at a linear velocity greater than the linear velocity at which such elements are driven, and a loose driving connection between said driven means and said driving means for allowing disconnection of the drive therebetween upon engagement of the respective objects of said

12

one set of objects with the respective elements of said one series of elements.

4. Apparatus for effecting registry of objects comprising driven means including an endless chain structure having an overlying and an underlying reach, an endless series of elements on said structure for engaging successive objects of a set of such objects, another endless series of elements on said structure for engaging successive objects of another set of such objects, the respective elements of the respective series being spaced to position said objects in desired relation for such registry, means for driving said driven means and chain structure, means for conducting one of said sets of objects under said underlying reach in the path of one of said series of elements at a linear velocity greater than the linear velocity at which such elements are driven, and a loose driving connection between said driven means and said driving means for allowing disconnection of the drive therebetween upon engagement of the respective objects of said one set of objects with the respective elements of said one series of elements.

5. Apparatus for effecting registry of objects comprising driven means including an endless chain structure having an overlying and an underlying reach, an endless series of abutment elements pivoted on said structure for engaging successive objects of a set of such objects, another endless series of abutment elements pivoted on said structure for engaging successive objects of another set of such objects, the respective abutment elements of the respective series being spaced to position said objects in desired relation for such registry, means for driving said driven means and chain structure, means for conducting one of said sets of objects under said underlying reach in the path of one of said series of elements at a linear velocity greater than the linear velocity at which such elements are driven, and a loose driving connection between said driven means and said driving means for allowing disconnection of the drive therebetween upon engagement of the respective objects of said one set of objects with the respective elements of said one series of elements.

6. Apparatus for effecting registry between creases on a carton blank and on a tab which is adapted to be secured to said blank with the creases in substantial registry comprising driven means, a series of elements on such driven means for engaging and moving successive tabs in one general direction, another series of elements on said driven means for engagement with successive blanks which are moved in such direction, the respective elements of the respective series being spaced to position said creases in desired relation for such registry, means for driving said driven means, and a loose driving connection between said driven means and said driving means for allowing disconnection of the drive therebetween upon engagement of the respective blanks with the respective elements of said another series.

7. Apparatus for effecting registry between creases on a carton blank and on a tab which is adapted to be secured to said blank with the creases in substantial registry, comprising driven means, and endless series of elements on said driven means for engaging and moving successive tabs in one general direction, another endless series of elements on said driven means for engagement with successive blanks, means for moving said blanks in said direction at a linear

velocity greater than the linear velocity at which the latter elements are driven, the respective elements of the respective series being spaced to position said creases in desired relation for such registry, means for driving said driven means, and a loose driving connection between said driven means and said driving means for allowing disconnection of the drive therebetween upon engagement of the respective blanks with the respective elements of said another series.

8. Apparatus for effecting registry between creases on a carton blank and on a tab which is adapted to be adhesively secured to said blank with the creases in substantial registry, comprising driven means, an endless series of elements on said driven means for engaging and moving successive tabs in one general direction, another endless series of elements on said driven means for engagement with successive blanks, means for moving said blanks in said direction at a linear velocity greater than the linear velocity at which the latter elements are driven, the respective elements of the respective series being spaced to position said creases in desired relation for such registry, means for driving said driven means, a pressure roller connected to said driving means for applying pressure to the respective registered blanks and tabs, and a loose driving connection between said driven means and said driving means for allowing disconnection of the drive therebetween upon engagement of the respective blanks with the respective elements of said another series, the position of said pressure roller with respect to said endless series of elements being such that the elements are disengaged from said blanks and tabs substantially when they become engaged by the pressure roller.

9. Apparatus for effecting registry between creases on a carton blank and on a tab which is adapted to be secured to said blank with the creases in substantial alinement, comprising driven means including a pair of endless chains, an endless series of abutment elements pivoted on one of said chains for engaging and moving successive tabs in one general direction, another endless series of abutment elements pivoted on the other of said chains for engagement with successive blanks, means for moving said blanks in said direction at a linear velocity greater than the linear velocity at which said chains are driven, the respective elements on the respective chains being spaced to position said creases in desired relation for such registry, means for driving said driven means, and a loose driving connection between said driven means and said driving means for allowing disconnection of the drive therebetween upon engagement of the respective blanks with the respective elements of said another series.

10. Apparatus for effecting registry between creases on a carton blank and on a tab which is adapted to be adhesively secured to said blank with the creases in substantial alinement, comprising driven means including a pair of endless chains, an endless series of abutment elements pivoted on one of said chains for engaging and moving successive tabs in one general direction, another endless series of abutment elements pivoted on the other of said chains for engagement with successive blanks, means for moving said blanks in said direction at a linear velocity greater than the linear velocity at which said chains are driven, the respective elements on the respective chains being spaced to position said creases in desired relation for such registry,

means for driving said driven means, a pressure roller connected to said driving means for applying pressure to the respective registered blanks and tabs, and a loose driving connection between said driven means and said driving means for allowing temporary disconnection of the drive therebetween upon engagement of the respective blanks with the respective elements of said another series, the position of said pressure roller with respect to said endless series of elements being such that the elements are disengaged from said blanks and tabs substantially when they become engaged by the pressure roller.

11. Apparatus for effecting registry between creases on a carton blank and on a tab which is adapted to be adhesively secured to said blank with the creases in substantial alinement, comprising driven means including a pair of endless chains, an endless series of abutment elements pivoted on one of said chains for engaging and moving successive tabs in one general direction, another endless series of abutment elements pivoted on the other of said chains for engagement with successive blanks, means for moving said blanks in said direction at a linear velocity greater than the linear velocity at which said chains are driven, the respective elements on the respective chains being spaced to position said creases in desired relation for such registry, means for driving said driven means, a pressure roller connected to said driving means for applying pressure to the respective registered blanks and tabs, each of said chains having an underlying reach leading to said pressure roller for engaging the respective blanks and tabs to said pressure roller, and a loose driving connection between said driven means and said driving means for allowing temporary disconnection of the drive therebetween upon engagement of the respective blanks with the respective elements of said another series, the position of said pressure roller with respect to said endless series of elements being such that the elements are disengaged from said blanks and tabs substantially when they become engaged by the pressure roller.

12. Apparatus for effecting registry between creases on a carton blank and on a tab which is adapted to be adhesively secured to said blank with the creases in substantial alinement, comprising driven means including a pair of endless chains, an endless series of abutment elements pivoted on one of said chains for engaging and moving successive tabs in one general direction, another endless series of abutment elements pivoted on the other of said chains for engagement with successive blanks, means for moving said blanks in said direction at a linear velocity greater than the linear velocity at which said chains are driven, the respective elements on the respective chains being spaced to position said creases in desired relation for such registry, means for driving said driven means, a pressure roller connected to said driving means for applying pressure to the respective registered blanks and tabs, each of said chains having an overlying and an underlying reach, the underlying reach of each chain leading to said pressure roller for engaging the respective blanks and tabs to said pressure roller, the overlying and the underlying reach of each chain being joined by an unright reach which is inclined inwardly toward the associated underlying reach at the turns of said chains where said elements engage the blanks and the tabs, and a loose driving connection between said driven means and said driv-

ing means for allowing temporary disconnection of the drive therebetween upon engagement of the respective blanks with the respective elements of said another series, the position of said pressure roller with respect to said endless series of elements being such that the elements are disengaged from said blanks and tabs substantially when they become engaged by the pressure roller.

13. The apparatus of claim 12 in which said turn of the tab chain is positioned ahead of said turn of the blank chain whereby the respective tabs are engaged by the respective elements on the tab chain prior to engagement of the respective blanks with the respective elements on the blank chain. 15

14. The apparatus of claim 12 in which the underlying reach of the tab chain is inclined downwardly toward said pressure roller, the means for moving the blanks comprises a belt, and the underlying reach of the blank chain rides substantially parallel to and closely adjacent said belt. 20

15. The apparatus of claim 12 in which said turn of the tab chain is positioned ahead of said turn of the blank chain whereby the respective tabs are engaged by the respective elements on the tab chain prior to engagement of the respective blanks with the respective elements on the blank chain, the underlying reach of the tab chain is inclined downwardly toward said pressure roller, the means for moving the blank comprises a belt, and the underlying reach of the blank chain rides substantially parallel to and closely adjacent said belt. 25

16. In registering apparatus of the character described, a plurality of laterally spaced cooperative endless chains each having registering elements thereon, laterally spaced sprockets about which said chains turn, a rotatable driving member located between said sprockets and having an arcuate slot therein, and a pin connecting said sprockets and extending through said slot whereby a loose driving connection is provided between said driving member and said sprockets. 30

17. In registering apparatus of the character described, driven means comprising a plurality of endless chains, each of said chains having an endless series of registering elements mounted

thereon, the spacing between the respective elements on the respective chains being such as to provide the desired registry, means for driving said chains in unison; and a loose driving connection between said driving means and said driven means allowing temporary disconnection of the drive therebetween. 5

18. In registering apparatus of the class described, an endless member adapted to be driven and having an endless series of registering elements thereon adapted to be successively engaged by successive objects to drive the member, means to drive said member independently of said objects, and a loose driving connection between said member and said driving means to allow said objects to drive said member. 10

19. In registering apparatus of the class described, an endless chain adapted to be driven and having an endless series of registering elements pivotally mounted thereon and which are adapted to be successively engaged by successive strips of material to drive the chain, means to move said strips into engagement with the respective elements, means to drive said chain independently of said strips and at a slower speed than the means for moving said strips, and a loose driving connection between said chain and said driving means to allow said strips to drive said chain in advance of said driving means. 20

20. The apparatus of claim 19 in which said endless chain has an upper reach and an under reach, the means to move said strips comprises an endless belt adjacent said under reach, and said registering elements are positioned to ride over said belt. 25

21. The apparatus of claim 20 in which guide means is provided to conduct each registering element in proper relation to said belt as it approaches the under reach of said chain. 30
